ABSTRACT

In a switching circuit connected between a letter selecting circuit and a luminescent letter display tube there is provided a transistor for each anode electrode of the display tube. The base electrode of the transistor is grounded, the emitter electrode is suitably biased, the collector electrode is connected to the anode electrode and the control signal is applied to the emitter electrode.

SWITCHING CIRCUIT FOR LUMINOUS DISPLAY TUBES**BACKGROUND OF THE INVENTION**

This invention relates to a switching circuit wherein a transistor is utilized to control a load by the switching action of the transistor.

To display letters by controlling the combination of a plurality of luminous electrodes of a fluorescent letter display tube it is necessary to select suitable luminous electrodes corresponding to a letter to be displayed.

Although many types of selecting circuits for this purpose have been proposed, usually a diode matrix circuit has been used.

To statically drive a fluorescent letter display tube (for brevity, hereinafter merely termed as display tube), it is usual to use a rated anode voltage ranging from 20 to 25 volts so that it is easy to use a selecting circuit of the monolithic structure. However, in order to dynamically drive the display tube it is necessary to set the anode voltage to about 50 volts so that it is impossible to use a monolithic integrated circuit.

To obviate this difficulty it has been proposed to provide a transistor between each one of the luminous electrodes and a letter selecting circuit. However, this arrangement requires some modification of the letter selecting circuit. To avoid such modification two transistors have been connected in cascade. However, this complicates the circuit construction.

SUMMARY OF THE INVENTION

It is an object of this invention to provide a simple and economic switching circuit for display tubes.

According to this invention there is provided a transistor between a conventional letter selecting circuit and each anode electrode of a luminous letter display tube. The base electrode of the transistor is grounded, the collector electrode is connected to the anode electrode and the emitter electrode is suitably biased. The control signal from the letter selecting circuit is applied to the emitter electrode. Depending upon a particular digit or letter to be displayed, the letter selecting circuit operates to select a suitable combination of anode electrodes to operate transistors connected to the selected anode electrodes.

BRIEF DESCRIPTION OF THE DRAWING

In the accompanying drawing a single figure shows a connection diagram of the switching circuit constructed according to the teaching of this invention.

DESCRIPTION OF THE PREFERRED EMBODIMENT

Referring now to the accompanying drawing a letter display tube 26 comprises a plurality of luminous anode electrodes *a* through *h*, a grid electrode 27 and a filament electrode 25 energized by a filament source 29. As is well known in the art suitable combinations of anode electrodes *a* through *h* are selected by a selecting circuit, not shown, to selectively display any one of digits 0, 1, 2 . . . 9, for example.

Anode electrodes are controlled by PNP transistors 33*a* through 33*h*. Different from the prior art connection, the base electrodes of these transistors are grounded, emitter electrodes are suitably biased through resistors 32*a* through 32*h*, collector electrodes are connected to loads, that is anode electrodes *a* through *h* and input signals from the letter selecting

circuit are applied to input terminals 34*a* through 34*h* which are connected to emitter electrodes. Anode electrodes *a* through *h* and collector electrodes of the transistors are connected to a source of positive potential 28 through resistors 33*a* through 33*h*, respectively.

The switching circuit operates as follows. Assuming now that anode electrode *a* is to be operated, then a positive signal is applied to input terminal 34*a* from the letter selecting circuit not shown. This signal creates a voltage drop across resistor 32*a* to positively bias the emitter electrode of transistor 31*a* to turn ON the same. Then the positive potential of the source 28 is applied to the anode electrode *a* of the display tube 26 through the ground, resistor 32*a* and the emitter-collector circuit of transistor 31*a*, thus causing anode *a* to luminescence. At this time since no signal is applied to terminal 34*h* anode electrode *h* does not luminesce.

Although a voltage drop is created across resistor 32*a*, since the current flowing through it is very small and since its resistance value is low (less than 1 kilo-ohms, ohms), provision 20 of this resistor does not affect the brightness of the light emanated. Resistors 32*a* through 32*h* may be replaced by level shift diodes of suitable polarity. Since the voltage drop is the same for all luminous electrodes, by slightly increasing the voltage of source 28 it is possible to produce uniform 25 brightness of the rated value.

For the sake of simplicity, in the foregoing description although the operation of the anode *a* alone has been described, it will be clear that a suitable combination of anode electrodes is to be selected by the letter selecting circuit to display a desired digit.

Thus, according to this invention it is necessary to use only one type of the letter selecting circuit thus greatly simplifying the circuit construction and saving the cost of manufacturing so as to improve reliability. The output from a bipolar integrated circuit now widely used in many systems, such as 35 table electronic computers and the like provides a positive output. A combination according to the present invention of the novel switching circuit and a letter selecting circuit is especially suitable to display digits on the fluorescent letter display 40 tube according to the output from such bipolar integrated circuit.

Although a particular embodiment has been shown and described, it will be clear that many modifications may be made without departing from the scope of the invention as 45 defined in the appended claim.

What is claimed is:

1. In a switching circuit connected between a letter selecting circuit and a plurality of anode circuits of a luminous letter display tube, the improvement which comprises for each said 50 anode circuit, a single transistor, means to ground the base electrode of said transistor, means to connect each collector electrode to a respective anode electrode of said display tube, means to bias the emitter electrode and means to apply a control signal from said letter selecting circuit to said emitter electrode.

2. The switching circuit according to claim 1 wherein said display tube comprises a plurality of luminous anode electrodes, said letter selecting circuits operate to select a suitable combination of said anode electrode to display a given letter, 60 and one of said transistor is provided for each anode electrode and is of the PNP type.
